US00D900643S

(12) **United States Design Patent** (10) **Patent No.:** **US D900,643 S**
(45) **Date of Patent:** **** Nov. 3, 2020**

(54) **WATCH WITH DISPLAY**

- (71) Applicant: **Garmin Switzerland GmbH**,
Schaffhausen (CH)
- (72) Inventors: **Brent E. Barberis**, Overland Park, KS
(US); **Todd P. Register**, Olathe, KS
(US); **Henry D. Wulfkoetter**, Kansas
City, MO (US)
- (73) Assignee: **Garmin Switzerland GmbH** (CH)
- (**) Term: **15 Years**
- (21) Appl. No.: **29/681,526**

(22) Filed: **Feb. 26, 2019**

(51) **LOC (12) Cl.** **10-02**

(52) **U.S. Cl.** **D10/38; D14/344**

(57) **CLAIM**

The ornamental design for a watch with display, as shown and described.

DESCRIPTION

FIG. 1 is a front perspective view of a watch with display according to the present invention;

FIG. 2 is a rear perspective view of the watch with display;

FIG. 3 is a top view of the watch with display;

FIG. 4 is a front view of the watch with display;

FIG. 5 is a bottom view of the watch with display;

FIG. 6 is a rear view of the watch with display;

FIG. 7 is a left side view of the watch with display; and,

FIG. 8 is a right side view of the watch with display.

The broken lines shown in the drawings represent portions of the watch with display that form no part of the claimed design.

1 Claim, 8 Drawing Sheets
